UNITED STATES PATENT OFFICE.

WILLIAM S. HADAWAY, JR., OF NEW ROCHELLE, NEW YORK, ASSIGNOR TO THE CUTLER-HAMMER MFG. CO., OF MILWAUKEE, WISCONSIN, A CORPORATION OF WISCONSIN.

REGULATOR.

1,282,221.

Specification of Letters Patent.

Patented Oct. 22, 1918.

Application filed March 26, 1914. Serial No. 827,362.

To all whom it may concern:

Be it known that I, WILLIAM S. HADAWAY, Jr., a citizen of the United States, and a resident of New Rochelle, county of West Chester, and State of New York, have invented certain new and useful Improvements in Regulators, of which the following is a specification, reference being had to the accompanying drawings, forming a part 10 thereof.

My invention relates to regulators and particularly to such as are adapted to govern electrically controlled devices in response to temperature variations at a more or less 15 remote point.

One object of my invention is to provide a regulator of the character above indicated that shall be not only susceptible of a nicely accurate adjustment, but also automatically 20 and quickly responsive, at any predetermined setting, to small variations from the regulated temperature corresponding thereto.

Another object is to provide a simple and compact regulator of the aforesaid character that shall be effective and reliable in operation and particularly adapted to govern the circuit from which energy is supplied to an electric heating device.

Another object is to provide a combination 30 embodying an actuator, a movable contact having a movement between predetermined limits, and means for permitting the actuator to overrun in either direction of movement without injuring the contact.

Other objects and advantages of my invention will be set forth hereinafter, and in order that my invention may be thoroughly understood I will proceed to describe the same in the following specification and then 40 point out the novel features thereof in appended claims.

Referring to the drawings:

Figure 1 is a front elevation with the cover removed of a regulator arranged and 45 constructed in accordance with my invention.

Fig. 2 is a partially sectional elevation at right angles to Fig. 1.

A detail plan view of the coöperating contact members is shown on a larger scale in 50 Fig. 3.

Figs. 4 and 5 are respectively side and front elevations of the movable contact member with its attachments, the scale to which

they are drawn corresponding to that of 55 Fig. 3.

Figs. 6 and 7 are respectively a front and side elevation of the spiral actuator which forms a part of the structure of Figs. 1 and 2.

Corresponding parts are designated by the 60 same reference characters in all the figures.

While I have indicated a use for which my improved regulator is well adapted, my invention is not limited in this regard and the device is capable of wide application. 65

In general, the structure illustrated comprises a casing 10, a frame 20, relatively stationary contacts 30, a movable contact 50, spring pressed arms 60, a pressure responsive spiral actuator 70, a swivel supporting plate 75 for the actuator and a thermometer 80.

The casing 10 is in the form of a box having lugs 11 projecting inwardly from its bottom surface, and a cover 12 removably secured to it by screws 13. The cover is 75 preferably provided with an opening 14 closed by a glass plate 15. The body of the box has a small lateral opening 16 through which a connecting tube of the thermometer extends. 80

The frame 20 is mounted on the casing lugs 11 and it is secured thereto by screws 21. It has at the top a hollow boss 22, and extending longitudinally through its center a slot 23. Near its lower end it is provided 85 with a transverse slot 24 which is at right angles to the slot 23, and it has, at the respective ends of the slot 24, upturned edges or ears 25. It may be conveniently stamped or punched from sheet metal. 90

Parallel to the slot 24 and extending between and supported by the ears 25 is a pin 26 and rotatively supported in parallelism with the pin is an adjusting screw 27. Opposite the head of the screw 27, which is 95 slotted to receive a screw-driver, is an opening 18 in the casing in order to permit the adjustment of the screw without removing the frame from the casing.

The stationary contact members 30 are in 100 the form of thumb screws which are inserted in tapped holes in a pair of contact posts 31. These posts are secured to and insulated from a carrier 32 which extends into the slot 24 in the frame and is mounted to be 105 adjusted longitudinally of the pin 26 by the screw 27. The carrier is tapped to receive the screw and is provided with a parallel

hole to receive the pin 26 both of which extend through it. The posts are spaced apart on the carrier and extend outwardly therefrom in the plane determined by the axes of 5 the pin and screw. The holes which receive the screw contacts 30 are in alinement with each other in the same plane and the screws may be locked in any position to which they are adjusted, by set screws 33. The posts 10 are provided with terminal extensions 34 to which circuit conductors (not shown) may be connected in a well-known manner. The mounting for the carrier is obviously such that it is readily adjustable transversely 15 of the regulator and, as more fully explained hereinafter, the contacts 30 may be set at a predetermined distance apart and then the carrier adjusted to determine their position relative to the movable contact. 20 An index or pointer 35 of the carrier is adapted to coöperate with a transverse scale strip 36 which is secured to the flanges 25 adjacent to the path of movement of the carrier. 25 A stationary post 51 extends outwardly from the boss 22 to which it is secured by a screw 52 and from which it is electrically separated by insulation 53. Rotatively mounted on the post near its outer end is a hub 56 which carries a pair of spaced 30 brackets 54. The brackets 54 support pins 55 in parallelism with the post 51. A strip or finger 57 is secured to the hub 56 and carries at its lower end a contact 50. The hub 56 has a projection 58 which is in alinement with the finger 57 but extends upwardly from the hub between the pins 55 which are above the center line of the post 51. The arms 60 are similar to each other and 40 each of them has a pair of spaced hub members 61 which are fitted onto one of the pins 55 and provides a rotatable mounting for the arm. Each arm is materially wider than the finger 57 so that there is a free space between the arms beneath the finger. Between the spaced hubs 61 on each of the pins 55 is a helical spring 62 which is under tension and has one end in engagement with the extension 58 of the hub 56 and the other end 45 50 55 60 64 in engagement with the arm which is mounted on the same pin. The arrangement of parts is such that the two springs 62 which are located on the respective pins press the arms 60 against the finger 57. The outer ends of the arms are bent inwardly as shown at 65 so that they are in engagement with the finger 57 only at one point which is substantially midway between its pivotal axis and the contact 50. 60 Since the arms 60 are mounted on the hub 56 of the finger against which they are pressed, they constitute yielding members thereof. They are provided for the purpose of permitting a wide movement of the 65 actuator without injuring the finger which

is clearly limited in its movement by the stationary contacts 30.

The actuator 70, as clearly shown in Fig. 6, is similar in structure to the corresponding part of a pressure gage, being composed 70 of a flattened tube which is bent into the form of a spiral. Connected to its inner end is a tube 71 which is preferably provided with an opening of capillary dimensions. The spiral is closed at its outer end and has 75 an enlargement or head 72. An actuating pin 73 is insulated from and mechanically connected to the head 72 and extends outwardly at right angles to the plane of the spiral, as clearly shown in Fig. 2. To the 80 outer end of the pin 73 is secured a roller 74 which is adapted to engage and act upon the one or the other of the arms 60.

The spiral actuator is supported at its inner end by a plate 76 which is in turn 85 secured to and forms a part of the swivel supporting plate 75. The swivel plate is in the form of a disk segment and has a circumferential slot 77 and a hole 78 at its center of curvature. 90

A strip 28 is located on the underside of the frame 20 beneath the longitudinal slot 23 and the swivel supporting plate 75 is adjustably mounted on the frame by screws 29 which respectively extend through the 95 slot 77 and the hole 78 and engage suitably spaced tapped holes in the strip 28.

The member 80 which, for convenience is designated as a "thermometer", comprises a tubular body which is connected to the 100 flattened tube of the spiral actuator by the tube 71. These connected members are preferably sealed by welding after having been filled with an expandible liquid such as mercury. 105

The tube 71 is relatively flexible and made of any required length, the thermometer 80 being subjected to the temperature to be regulated; for example, the thermometer may be introduced into a crucible for a type-setting machine for the purpose of regulating the heat generated in the crucible heaters. A crucible and suitable heaters therefor, which may be conveniently governed by my regulator, are shown and described in 110 115 my copending application Serial Number 827,361, filed of even date herewith.

The operation of the regulator is as follows: Assuming that the normal temperature to be maintained by the regulator and to which the thermometer 80 is exposed is 530 degrees F., the parts of the regulator will occupy positions in which they are shown in Fig. 1 when the thermometer 80 is heated exactly to 530 degrees. Should the temperature of the thermometer be increased the spiral actuator 70 will be expanded and since its inner end is rigidly affixed to the frame 20 its outer end will move in a clockwise direction with respect to Fig. 1, and the 125 130

roller 74 of the actuating pin 73 will act upon the arm 60 which is in the path of the expansive movement, thereby forcing the movable contact 50 into engagement with one of the stationary contacts 30. The actuator may continue to expand so that the pin continues to act upon one of the arms 60, but the only effect will be to swing the arm on its pivot in opposition to its spring 10 and the finger 57 will not be subjected to excessive stresses which might otherwise destroy it or bend it sufficiently to destroy the accuracy of the instrument. A circuit (not shown) may be completed by 15 these contacts in a well known manner and cause a reduction of the heat to which the thermometer is subjected. If, for example, the regulator governs an electric heater the circuit of the heater may be temporarily 20 interrupted.

When the temperature is restored to 530 degrees which was assumed as a normal temperature, the parts will return to the positions in which they are shown in Fig. 1. 25 If, on the other hand, the temperature to which the thermometer is subjected falls below 530 degrees, the spiral actuator will be contracted, the roller 74 of the actuating pin being moved in a counter-clockwise direction. It now acts upon the opposite arm 60, and forces the movable contact 50 into engagement with the other stationary contact 30. A circuit may now be established which is adapted to increase the heat to which the 35 thermometer is subjected. In case the regulator is governing an electric heater the supply circuit of the heater may be closed.

Of course, some means is preferably provided for substantially maintaining the device 40 sired temperature and an auxiliary heating device energized and deenergized by the regulator. Inasmuch as arrangements of this character form no part of my present invention which is concerned only with the 45 regulator, I deem it unnecessary to illustrate or describe the devices governed by the regulator.

When the flattened spiral actuator 70 is inactive, the thermometer being at ordinary 50 room temperature, it is contracted as shown in Fig. 6, the actuating head 72 being materially displaced from the central radius of the sector 75. Under these conditions it is evident that the arm 60, to the left in Fig. 55 1, will be displaced from the position in which it is illustrated by a material angle, the movable contact 50 being in engagement with the left-hand stationary contact 30.

The spiral actuator is preferably designed 60 to operate at approximately the temperature required but it is frequently desirable to adjust the regulator in various ways as follows: As already pointed out the actuator, together with its attached carrier 75, are adjustable longitudinally of the frame 20. By

this means the head 72 and the pin 73 may be adjusted to act upon the arm 60 at a greater or less distance from their pivotal centers. This adjustment will affect to a certain extent the sensitiveness of the regulator because by this means the deviation of the head necessary to permit engagement between the movable contact and one of the stationary contacts is varied. Since the carrying sector 75 is rotatively adjustable, the 70 spiral actuator may be set without difficulty when inactive, to such a position as to bring the head into the central plane of the regulator at the predetermined normal temperature. 75

Furthermore, a very careful adjustment may be effected between the two stationary contacts 30 to secure the desired spacing. Then by means of the screw 27 the position of the carrier 32 may be carefully adjusted 80 transversely of the regulator so that contact will be effected with one or the other of the stationary members by the movable contact in response to corresponding and equal but opposite variations in the temperature, to 85 which the thermometer is subjected.

It is evident that the frame, to which all the active parts of the device are attached, is readily removable from the casing by merely releasing the screws 21. While the 90 casing protects the apparatus from injury and dust the position of the movable contact and the setting of the carrier 32 with reference to the scale 36, may be observed through the glass plate 15. 95

Variations in size and arrangement of details may obviously be effected within the spirit and scope of my invention, and I intend that only such limitations be imposed as are indicated in the appended claims. 100

What I claim is:

1. A regulator comprising a movable member, means restricting the range of movement of said member in either direction, two yielding arms on said movable member, and means acting upon one or the other of the arms to actuate the movable member in either direction, whereby said last named means is free to move through a greater range than said movable member. 110

2. A regulator comprising stationary contacts, a movable contact adapted to swing between and into engagement with the stationary contacts, yielding arms on said movable contact, and means acting upon one or the other of the yielding arms to actuate the movable contact into engagement with one or the other of the respective stationary contacts. 120

3. A regulator comprising a pair of stationary contacts, a movable contact pivotally supported and adapted to swing between and into engagement with the stationary contacts, a pair of arms pivotally mounted on the movable contact, springs 125

- 4
- pressing the arms against the contact, and means acting upon the arms to actuate the movable contact.
4. A regulator comprising a casing, a frame removably secured therein, a post secured to and insulated from the frame near one end, a movable contact pivotally mounted on said post, a pair of spring-pressed arms mounted on and pressing against the movable contact, a pair of independently adjustable stationary contacts adapted to co-operate with the movable contact, a carrier for the stationary contacts adjustably mounted on said frame, a temperature responsive actuator arranged to act upon the one or the other of said arms, and a carrier for the actuator rotatively and longitudinally adjustable on said frame. 70
5. A regulator comprising a casing, a frame removably secured therein, a post secured to and insulated from the frame near one end, a movable contact pivotally mounted on said post, a pair of spring-pressed arms mounted upon and pressing against the movable contact, a pair of independently adjustable stationary contacts adapted to co-operate with the movable contact, a carrier for the stationary contacts adjustably mounted on said frame, a temperature responsive actuator arranged to act upon the one or the other of said arms, and a carrier for the actuator rotatively and longitudinally adjustable on said frame. 75
6. A regulator comprising a casing, a frame removably secured therein, a post secured to and insulated from the frame near one end, a movable contact pivotally mounted on said post, a pair of spring-pressed arms mounted upon and pressing against the movable contact, a pair of independently adjustable stationary contacts adapted to co-operate with the movable contact, a carrier for the stationary contacts adjustably mounted on said frame, a flattened tube spiral actuator arranged to act upon the one or the other of said arms, a sector affixed to the inner end of said spiral and having a circularly curved slot, and means for adjustably securing the sector to said frame to permit a rotative and a straight line adjustment thereof. 80
7. A regulator comprising a casing, a frame removably secured therein, a movable contact pivotally supported by said frame, a pair of spring-pressed arms mounted upon the movable contact, a pair of independently adjustable stationary contacts adapted to co-operate with the movable contact, a carrier for the stationary contacts adjustably mounted on said frame, a temperature responsive actuator arranged to act upon the one or the other of said arms, and a carrier for the actuator rotatively and longitudinally adjustable on said frame. 85
8. A regulator comprising a movable contact, a pair of spring-pressed arms acting upon opposite sides of the movable contact, a pair of independently adjustable stationary contacts adapted to co-operate with the movable contact, an adjustably supported carrier therefor, and a temperature responsive actuator arranged to act upon the one or the other of said arms. 90
9. A regulator comprising a movable contact, a pair of spring-pressed arms acting upon opposite sides of the movable contact, a pair of stationary contacts adapted to co-operate with the movable contact, and means adapted to act upon the one or the other of said arms to actuate the movable contact. 95
10. A regulator comprising a movable contact, a pair of spring-pressed arms acting upon opposite sides of the movable contact, a stationary contact adapted to co-operate with the movable contact, and means adapted to act upon the one or the other of said arms to actuate the movable contact. 100
11. In combination, a movable member, opposed resilient means mounted on the movable member and pressing against it, and means for acting upon one or the other of said means to actuate the member to move in one direction or the other into an active position. 105
12. The combination with stationary members, a movable member adapted to move in one direction or the other into engagement with a stationary member, of a pair of yielding arms mounted on the movable member, and a temperature responsive spiral having an actuating member adapted to act upon one or the other of said yielding arms when the spiral is expanded or contracted. 110
13. The combination with a movable contact adapted to swing in one direction or the other into engagement with a stationary contact, having a pair of opposed yielding members, of a temperature responsive spiral having an actuator projection adapted to act upon one or the other of said yielding members when the spiral is expanded and contracted from a mean position corresponding to a predetermined temperature. 115
14. A regulator comprising a pair of stops or limits, a movable member adapted to swing between said stops or limits and having a pair of outwardly yielding parts, each of said parts being adapted when moved outwardly to transmit motion to said member until it abuts against one of said stops or limits and then to yield outwardly, and an actuator having a projection extending between said parts and adapted to move the movable member between said limits in response to its own movement, without being restricted by said limits in either direction. 120
15. A regulator comprising a pair of spaced stationary contacts, a movable contact member adapted to swing between said stationary contacts and having a pair of outwardly yielding parts, each of said parts being adapted when moved outwardly to transmit motion to said member until it abuts against one of said contacts and then to yield outwardly, and an actuator having a projection extending between said parts and adapted to move the movable member between said limits in response to its own 125

movement, without being restricted by said limits in either direction.

16. A regulator comprising a pair of spaced stationary contacts, a movable contact member adapted to be swung between said stationary contacts and having a pair of outwardly yielding parts, each of said parts being adapted when moved outwardly to transmit motion to said member until it abuts against one of said contacts and then to yield outwardly, and an actuator having a projection extending between said parts and adapted to move the movable contact member between said stationary contacts in response to its own movement, without being restricted by said contacts in either direction.
17. A regulator comprising a pair of stationary contacts, a pivoted contact arm adapted to swing between said contacts and having a pair of outwardly yielding fingers, each of said fingers being adapted when moved outwardly to transmit motion to said member until it abuts against one of said contacts and then to yield outwardly, and an actuator having a projection extending between said fingers and adapted to move the contact arm between and into engagement with said contacts in response to its own movement without being restricted in either direction by said contacts.

18. A regulator comprising a frame, a movable contact pivotally mounted thereon, a pair of independently adjustable stationary contacts adapted to coöperate with the movable contact, a carrier for the stationary

contacts adjustably mounted on the frame, a temperature responsive actuator for the movable contact, and a carrier for the actuator rotatively and longitudinally adjustable on said frame.

19. A regulator comprising a casing, a frame removably secured therein, a movable contact pivotally mounted on the frame, a pair of independently adjustable stationary contacts adapted to coöperate with the movable contact, a carrier for the stationary contacts adjustably mounted on the frame, a flattened tube spiral actuator for the movable contact, a sector affixed to the inner end of said spiral, and means for adjustably securing the sector to the frame to permit a rotative and a straight line adjustment thereof.

20. A regulator comprising a movable contact having a pair of oppositely yielding parts, a pair of independently adjustable stationary contacts adapted to coöperate with the movable contact, and an actuator extending between and acting upon one or the other of said parts to determine the position of the movable contact between the stationary contacts, without being limited in either direction by said contacts.

In witness whereof, I have hereunto set my hand this 24 day of March, 1914, in the presence of two subscribing witnesses.
